UNITED STATES PATENT OFFICE.

JAMES H. BUSELL, OF BOSTON, MASSACHUSETTS.

HEEL-BURNISHING MACHINE.

SPECIFICATION forming part of Letters Patent No. 392,715, dated November 13, 1888.

Application filed October 28, 1887. Serial No. 235,000. (No model.)

To all whom it may concern:

Be it known that I, JAMES H. BUSELL, of Boston, in the county of Suffolk and State of Massachusetts, have invented certain new and useful Improvements in Heel-Burnishing Machines, of which the following, taken in connection with the accompanying drawings, is a specification.

My invention relates to a machine for burnishing boot and shoe heels, is an improvement upon the invention described in another application of mine filed April 16, 1887, Serial No. 235,022, and consists in certain novel features of construction, arrangement, and combination of parts, which will be readily understood by reference to the drawings and to the claims to be hereinafter given, and in which my invention will be particularly pointed out.

Figure 1 of the drawings is a front elevation of a machine embodying my invention with the jack in position for burnishing the central portion of the heel-edge. Fig. 2 is a side elevation of the same with the jack in position for placing the boot or shoe thereon or removing it therefrom. Fig. 3 is an elevation of the head of the machine removed from the supporting-column. Fig. 4 is a plan of the same. Fig. 5 is a plan of the supporting-column with the head removed and the jack in position for removing the shoe therefrom. Fig. 6 is a plan of a portion of the jack-lever and the adjustable last-supporting pin. Fig. 7 is an end elevation of the same. Fig. 8 is a section on line xx on Fig. 6, but showing the last-supporting pin in elevation.

In the drawings, A is the column, supported by the legs A'. B is the driving-shaft, carrying the pulleys C, C', and C''. D is the frame of the head of the machine; E, the crank-shaft for operating the reciprocating burnishing-tool, and carrying the pulley F and hand-wheel G; H, the vertically-reciprocating tool-carrier. J is the belt for transmitting motion from the driving-shaft B to the shaft E. K is a bracket bolted to the side of the frame D, and having mounted in bearings thereto the shaft L, carrying at one end the pulley L' and at its other end a heel-seat burnishing tool, M, to which rotary motion is imparted by the belt N, leading from the pulley L' to the pulley N' on

the driving-shaft B; and O is the jack-rod; O', the jack-lever; P, the jack-supporting stand; Q, the jack-controlling spring, and R the spring adjusting and supporting bent rod, all 55 constructed, arranged, and operating substantially as shown and described in said prior application herein referred to.

I will now proceed to describe the improvements which constitute my present invention, 60 and for which I desire to obtain Letters Patent.

In the operation of the machine described in my said prior application I have found it somewhat inconvenient to hold the jack-rod away from the burnishing-tool against the tension of its spring while removing a shoe from the jack and placing another thereon. To obviate this difficulty I clamp upon the jack-rod O the hook O' and firmly secure to the base of the column A an arm, O'', with the upper end of 70 which the hook O'' engages when the jack is swung to the left and rear of Fig. 1, as shown in Figs. 2 and 5, in which position the jack will be firmly held by the tension of the spring R, so that the operator has both hands free for 75 use in applying the shoe to or removing it from the jack. This is a very great advantage. I have also found that the holes in the tops of the heel portions of the lasts are not always bored at the same distance from the 80 rear end of the last, and also that the heels of boots and shoes do not always bear the same relation to the rear of the boot or shoe. It is, however, very desirable that the boot or shoe should be so jacked that it shall rotate about 85 an axis corresponding as nearly as possible to the center of the heel in all cases. In order to attain this very desirable end, I secure to the inner end of the jack-lever O', by means of the pivot-screw a, the arm b, provided with 90 the longitudinal dovetailed groove c, in which is fitted so as to be movable endwise therein the block d, which may be clamped in any desired position in said groove by the last-supporting pin S, the main body of which is made 95 many-sided and tapering, and provided with the collar e, to bear upon the face of the arm b upon each side of the groove c, and with the screw-shank f, to screw into a correspondingly-threaded hole in the block or nut d, all as 100 shown in Figs. 6, 7, and 8.

By making the main body of the pin S po-

lygonal in cross-section and tapering, it is adapted to fit holes of different sizes in the lasts, and the last is effectually prevented from revolving about said pin; but the last and shoe 5 thereon, together with the pin S and the arm b, are made to revolve about the axis of the pivot-screw a, and it will therefore be readily seen that by so adjusting the block d and the pin S that the axis of the pin S shall bear the 10 same relation to the axis of the pivot-screw a that the hole in the last does to the center of the heel the vibrations of the jack due to rotating the shoe-heel while in contact with the burnishing-tool will be reduced to a minimum.

15 What I claim as new, and desire to secure by Letters Patent of the United States, is—

1. In a burnishing-machine having a universally-movable jack-rod and a spring for moving the free end of said jack-rod toward 20 the burnishing-tool, a hook fixed upon said jack-rod, in combination with a fixed arm or stop to engage said hook when said jack-rod is moved into a certain predetermined position and hold said jack in said position.

2. The combination, with the jack-rod O and 25 the jack-lever O', of the arm b, pivoted to said lever and provided with a dovetailed slot or groove extending longitudinally thereof, the block or nut d, fitted to said dovetailed groove, and a last-supporting pin screwed into said 30 block and adapted to clamp it in any desired position in said groove.

3. In a boot or shoe supporting jack, the 35 combination of a pivoted arm and a pin to enter the hole in the shoe-supporting last, adjustably secured in said pivoted arm, with its axis parallel to the pivotal axis of said arm, and having its main body made polygonal in cross-section and tapering toward its free end.

In testimony whereof I have signed my name 40 to this specification, in the presence of two subscribing witnesses, on this 22d day of October, A. D. 1887.

JAMES H. BUSELL.
